UNITED STATES PATENT OFFICE

SAMUEL B. DRUCKER, OF BROOKLYN, NEW YORK

EMULSIFYING APPARATUS

Application filed October 19, 1928. Serial No. 313,482.

This invention relates to improvements in emulsifying apparatus. More particularly, my invention relates to emulsifying apparatus of the character including a rotary vessel or receptacle and a stationary amalgamating member which serves, during rotation of the vessel, to break up constituents, such as eggs, oil, vinegar and similar ingredients, into an emulsified mass comprising mayonnaise.

It is an object of my invention to combine with an emulsifying apparatus including a platform adapted to be rotated, of a receptacle arranged to be detachably secured to said platform, the receptacle being arranged to be disposed relatively to a stationary beater or amalgamating member positioned therein. It is contemplated by my invention to provide engaging means between the rotating platform and a receptacle mounted thereon, particularly the bottom thereof, in the nature of a lug on one and a notch on the other, the mere weight of the vessel keeping the notch and lug in engaging relation and is separable therefrom, for unloading the contents of the vessel after completion of the process or other operations, by lifting the vessel off the platform. It is further contemplated by my invention in its preferred form to provide a vessel made of wood or similar material which will best serve to aid in the amalgamation of emulsifying process in the nature of a keg, which has at the bottom thereof a centering stud engaging a shaft or extension of the same on the platform and also includes at the peripheral bottom walls, slots for engaging studs on the rotatable platform.

It is a particular object of my invention to provide engaging means between a rotatable platform and a vessel adapted to be mounted thereon, of engaging lugs on the platform and complementary slots on the receptacle, the slots on the receptacle being so disposed to readily and quickly slip over engaging lugs on the platform when the vessel rests on the platform, the walls being provided with shock absorbing side walls and reinforcing members whereby lost motion is avoided and in rotation of the platform, the vessel will be drawn therewith by sud-

denly starting the platform, without lost motion or a tendency to disrupt the slot. It is further contemplated by my invention to provide in an emulsifying apparatus, including a rotatable platform, a vessel adapted to be mounted thereon made of relatively soft material, such as wood, and including slots adapted to engage complementary lugs on the platform, the slots being provided with side walls to resist the shock of sudden turning movement of the platform and the engaging lugs fitted thereon.

To attain these objects and such further objects as appear herein or may be herein-after pointed out, I make reference to the accompanying drawing forming a part hereof, in which

Figure 1 is a perspective view, partly in section, showing my device;

Figure 2 is a section taken on a line 2—2 of Figure 1;

Figure 3 is a section taken on the line 3—3 of Figure 2;

Figure 4 is a bottom view of a portion of the receptacle;

Figure 5 is a perspective view of a detail.

Making reference to the drawing, it will be observed that my device comprises an emulsifying apparatus 10 comprising a base 11, upon which is mounted a rotatable platform 12, adapted to be driven by suitable driving means within the base 11 (not shown). Disposed to one side of the base 11, there is a standard 13, serving to support a container 14 for holding materials, and which also fixedly mounts a stationary amalgamating member 15, held removably in position by the set screw member 16. The platform 12 is arranged to have mounted thereon the amalgamating vessel 17, into which is disposed the stationary member 15, previously described. Emulsification is obtained of materials deposited within the container 17 by relative rotation of the amalgamating member 15 and the vessel 17. For mounting and rotating the vessel 17, the platform 12 is provided with a centering stud 18 and diametrically disposed lugs 19. The stud 18 is formed to enter a socket 20, in the bottom of the vessel 21, and is reinforced by the washer 22.

The vessel 17 has its side walls or slots forming the same extended beyond the bottom at 23 and provided with slots 24, of a size slightly larger than the lugs 19. For resiliently disposing the wall 24 relatively to the lugs 19, I dispose within the side walls 25 and 26, the angular members 27. These members comprise branches 28 and 29, the ends of which include spurs 30. For disposing the elements 27 in position, the branch 29 engages the outside edge of the vessel into a countersunk portion and is held in position by the screws 31, passing through the orifices 32 therein provided. The branch 28 has the end thereof angularly disposed and bent at 33, to inwardly direct the spurs 34 into the side walls 25 and 26 of the slot, at the same time maintaining the branch 28 slightly spaced from the walls 25 and 26, thereby forming the slot 24 slightly tapered by the angular position assumed by these members. It will be observed that to affix these into position, the spurs 34 are driven into the side walls 25 and 26, respectively. In mounting the vessel upon the turntable, the slots 24 will readily slip over the lugs 19 and serve, at the same time, to guide the stud 18 into the orifice 20. The addition of pressure will serve to force the lug 19 into the slot 24 and by reason of the angular position of the members 27, and particularly the branch 28 thereof, snug engagement of the slot and lug will be obtained. Engagement of the vessel 17 will thereby be had for rotation with the turntable 12, the members 27, serving to take up any free movement and give resilient contact between these parts, thereby avoiding any breakage due to the clearance allowed between the slot and the engaging lug.

In using vessels of lighter weight, the position upon the turntable will be more accurately assumed and prevent accidental displacement until the full contents are deposited within the vessel.

It will be further observed that I may form upon the turntable the upwardly extending flange 35, forming an annular space 36, into which the edge 23 of the vessel may be seated. It will be understood, however, that this flange 35 may be dispensed with entirely, suitable engagement being had by the gasket 20 and the stud 18.

It will thus be observed, by the structure, described, that I have provided a simple and efficient emulsifying apparatus and readily disengageable driving means between a rotatable member and the vessel mounted thereon.

Having thus described my invention and illustrated its use, what I claim as new and desire to secure by Letters Patents, is—

1. In an emulsifying apparatus for mayonnaise or the like including a rotatable platform, a non-metallic vessel adapted to be mounted thereon to be rotatably carried by

said platform, metallic engaging means between said vessel and said platform including a slot on one and a metallic lug on the other, said slot being formed with reinforced resilient lug engaging members for the non-metallic portions forming the walls thereof.

2. In an emulsifying apparatus including a rotatable platform, a wooden vessel adapted to be mounted thereon for rotation therewith, means on said platform for centrally positioning said vessel and engaging means between the vessel and platform comprising upstanding lugs, slots on said vessel adapted to releasably engage said lugs formed in the wooden walls of said vessel, said slots being formed with resilient reinforced side walls.

3. In an emulsifying apparatus including a rotatable platform, a wooden disengageable vessel adapted to be mounted thereon and including driving engagement by a lug on one and a slot on the other the slot being formed in the wooden walls of said vessel, of resilient reinforcing members for the side walls said slot adapted to engage the side walls thereof comprising an angular bent sheet metal strip, the branches whereof include wood engaging spurs, orifices on one branch adapted to receive fastening elements whereby said spurs may be driven into engaging position, the other branch being formed with an angularly disposed portion for resiliently spacing said branch from the wall on said slot.

In witness whereof I have hereunto signed my name this 16th day of August, 1928.

SAMUEL B. DRUCKER.
